UNITED STATES PATENT OFFICE.

EDWARD E. REDFIELD, OF GLENDALE, OREGON.

FIREARM.

1,343,583.

Specification of Letters Patent. Patented June 15, 1920.

Application filed October 4, 1919. Serial No. 328,461.

To all whom it may concern:

Be it known that I, EDWARD E. REDFIELD, a citizen of the United States, residing in Glendale, in the State of Oregon, have invented certain new and useful Improvements in Firearms, of which the following is a specification, reference being had to the accompanying drawings, forming a part hereof.

10 This invention has been developed with particular reference to the improvement of shot-guns used in trap shooting, the general purpose being to improve the construction of guns provided for that purpose so as to 60 enable them to withstand better the severe conditions of use to which such guns are subjected. Nevertheless, some or all of the 65 improvements to be described are capable of application to firearms of other types and the invention, therefore, is not limited to firearms of the particular type mentioned. Furthermore, the several improvements hereinafter described are not necessarily dependent one upon another, except as herein- 70 after pointed out and some of such improvements are capable of independent use.

75 The invention relates in part to the mounting of the barrel in the frame, the purpose being primarily to avoid putting all of the strain, when the gun is fired, on the hinge pin by which the barrel is usually secured in the frame and to distribute such strains more widely. Again, the interrelation of the frame and barrel is such as to cause the 80 barrel to be held with great firmness when the gun is closed, means being also provided to insure the engagement of the barrel and frame and to prevent the lifting of the barrel when the gun is closed without strain on 85 the fore-end at the time of firing. Another feature of the invention relates to the means whereby the fore-end is locked to the barrel and absolute security against accidental throwing off, which sometimes happens with 90 other guns when they are fired, is assured. The means for operating the ejector are also improved, with a view to securing the slow starting of the empty shell when the 95 opening movement of the gun begins, and to securing the subsequent kick or fillip necessary to complete the ejection of the shell. Another feature of the invention resides in the devices by which the hammer is cocked by the movement of the barrel when 100 the gun is open. The construction of the hammer mechanism has also been improved

in the way of simplicity and avoidance of a multiplicity of parts. Other features of improvement will be disclosed and pointed out in the claims. The invention will be 105 more fully explained hereinafter with reference to the accompanying drawings in which is shown a single barreled shot-gun to which the several improvements are applied and in which—

110 Figure 1 is a general view in side elevation and on a relatively small scale of a gun which embodies the invention.

Fig. 2 is a view on a larger scale, partly in side elevation as seen from the right hand side of the gun and partly in longitudinal section on the plane indicated by the broken line 2—2 of Fig. 3, the gun being shown as closed.

Fig. 3 is a view of the gun as seen from 75 above, with parts broken away in horizontal section to show details of construction.

Fig. 4 is a view similar to Fig. 2, but with the gun broken and some of the parts in different positions.

Fig. 5 is a detail view in horizontal section on the plane indicated by the broken line 5—5 of Fig. 2.

Fig. 6 is a detail view, in side elevation as seen from the left hand, with some parts 85 in section and broken away.

Fig. 7 is a detail view in horizontal section on the plane indicated by the broken line 7—7 of Fig. 6.

Fig. 8 is a detail view in elevation and 90 partly in longitudinal section on the plane indicated by the broken line 8—8 of Fig. 5.

Fig. 9 is a detail view in section on the plane indicated by the broken line 9—9 of Fig. 2.

95 Figs. 10, 11, 12, 13 and 14 are detail views in perspective showing respectively the hammer, the cocking lever, the barrel lock, the eccentric lever for releasing the fore-end and a portion of the lock mechanism.

100 Fig. 15 is a detail view in section on the plane indicated by the broken line 15—15 of Fig. 2.

Fig. 16 is a detail view in section on the plane indicated by the broken line 16—16 of Fig. 15.

105 The complete gun, as shown in Fig. 1, comprises the stock *a*, barrel *b*, frame *c* and fore-end *d*. The frame receives the lock mechanism and the barrel lock, as herein- 110 after described, and has two side flanges or cheek pieces *c'* between which the rear por-

tion of the barrel b is received snugly, the space between the side flanges, at the lower side, being closed by a web c^2 . The forward end of the frame, at its lower side, between the side flanges, as at c^3 , is rounded on the arc of a circle and the rear ends of the side flanges are cut off on the arc of a circle struck from the same center, as at c^4 . The two arcs are of concentric circles of different radii. The rear end of the fore-end d has a partially cylindrical seat, as at d' , to conform to the partially cylindrical end c^3 of the frame and the barrel b , near its rear end, is provided with shoulders b' curved to conform to the curved rear ends c^4 of the side flanges c' . When the fore-end is secured to the barrel, as hereinafter described, the barrel is therefore hinged to the frame on the center on which the curves b' , c^4 and c^3 , d' are struck, and may be swung about that axis, excessive swinging movement, such as would permit the separation of the barrel from the frame, being prevented by the bearing of the lip at the under side of the seat d' against the under side of the frame, as shown clearly in Fig. 4. The barrel is therefore held rigidly in the frame when the gun is closed and the strain at the instant of explosion is transmitted from the barrel to the frame through extended surfaces, the use of a hinge pin, which sometimes breaks, being avoided.

The fore-end d is formed as usual to fit snugly against the under side of the barrel b and is formed, near its forward end, with a notch d^2 , the forwardly facing shoulder of which fits snugly against the rearwardly facing shoulder of a lug b^{12} , secured as usual on the under side of the barrel. The wooden part d of the fore-end receives the metal frame d^3 , in the rear end of which is formed the partially cylindrical seat d' . The metal frame d^3 also receives the spring pressed locking bolt d^4 which engages the hooked lug b^2 , secured as usual to the under rib of the barrel and formed, as clearly shown in Fig. 8, with a flat shoulder b^3 , parallel with the axis of the barrel and the path of the movement of the bolt d^4 , so that absolute security against the throwing off of the fore-end by the flip which occurs when the gun is fired, is assured. A cam lever d^5 , pivoted in the metal part d^3 of the fore-end, exposed for operation through a slot in such metal part, and held normally in closed position by a spring d^6 , bears against the forward end of the locking bolt d^4 and acts upon the bolt to disengage the same from the hooked lug b^2 when it is desired to remove the fore-end from the gun for the purpose of permitting the gun to be taken down.

The rib b^4 , on the under side of the rear portion of the barrel, within the frame, as shown most clearly in Figs. 2 and 4, has a square hook b^5 at its forward end which en-

gages under a square shoulder c^6 at the forward end of the frame and so prevents the barrel from being lifted from the frame when the gun is closed, with no strain on the fore-end at the time of explosion.

The ejector e , as shown in Figs. 2, 4 and 5 is carried by a rod e' mounted in a channel formed in the upper part of the rib b^4 on the under side of the barrel, and is acted upon to start the empty shell slowly from the chamber of the barrel as the opening movement of the gun is commenced, by an L-shaped lever e^2 which is pivoted at its lower end in a slot b^6 , cut in the forward end of the rib b^4 and when the gun is closed stands with its rear face in contact with the end of the rod e' and its forward end against the rear end of a spring pressed plunger mounted in the fore-end d , the plunger being then in its extreme forward position. In this position the lever e^2 , as shown in Fig. 5, rests upon the forward end of the frame so that in the beginning of the opening movement of the gun the lever e^2 is, by movement relative to the frame, swung rearwardly on its pivot and starts the shell slowly from the chamber. The plunger has on its under side a rearwardly facing shoulder e^4 which, when the gun is closed, engages a forwardly facing shoulder of the metal part d^3 of the fore-end. In the closing movement of the gun the ejector bears against the face of the frame and is forced forwardly, at the same time, through the lever e^2 , forcing the plunger e^3 forward, from the position shown in Fig. 4 to the position shown in Fig. 2. Near the end of the opening movement of the gun a shoulder e^6 contacts with the under side of the rear end of the plunger e^3 and disengages the shoulder e^4 from the shoulder d^3 , permitting the plunger to be thrown rearwardly by its spring against the lever e^2 and the extractor rod, thereby completing the operative movement of the extractor and extracting the shell clear of the chamber.

The hammer f , as shown particularly in Figs. 2, 4, 9 and 10, is mounted on a pin f' in the lock plate and trigger guard which is held in the frame and secured by screws f^3 . The hammer f is acted upon directly by the mainspring plunger f^4 and has on its hub a cocking shoulder f^5 , which is engaged directly by the spring pressed trigger f^6 . The hub of the hammer is also provided with a cam f^7 which, in co-operation with the forward end of the trigger, when the hammer has reached its extreme forward position, effects the rebounding movement of the hammer and holds it with the firing pin withdrawn within the face of the frame. The hub of the hammer is also provided with a cocking shoulder f^8 which is engaged by the corresponding shoulder f^9 of a cocking lever f^{10} (shown most clearly in Fig. 120)

2, 4 and 11) which is also pivoted on the pin f' and is adapted to be actuated by the movement of the barrel in the opening of the gun, the cocking lever being extended forward and having a finger f^{11} . In the web b^4 on the under side of the barrel b , is mounted a yielding pin b^7 which has its right hand end beveled off and shouldered, as shown at b^8 in Fig. 15, and is pressed yieldingly to the right by a spring b^9 located partly in a shouldered recess b^{10} formed in the rib b^4 and partly in a shouldered recess b^{11} formed in the pin b^7 . The movement of the pin b^7 to the right is limited by a screw b^{12} which engages the left hand end of the pin, with its head overlapping the rib b^4 , as clearly shown in Fig. 16. In assembling the gun the pin contacts with the finger f^{11} of the cocking lever f^{10} and is forced to the left until it snaps back to the right under the finger f^{11} , as shown in Figs. 2, 15 and 16. Then, when the gun is broken, the pin b^7 lifts the cocking lever f^{10} from a position shown in Fig. 2 to the position shown in Fig. 4, this movement of the cocking lever swinging the hammer f rearwardly until its cocking shoulder f^5 is engaged by the trigger f^6 . The hammer is therefore cocked during the breaking movement of the gun and the gun is in readiness for firing as soon as it is closed.

The barrel lock comprises two bolts g and g' connected by a web g^2 , as shown in Fig. 12, the web having an opening g^3 . The locking bolts and web are mounted in suitable ways formed therefor in the upper part of the frame. Also mounted in the frame is the barrel locking lever g^5 , held in its seat in the frame by a spring pressed plunger g^6 which enters a groove in the hub g^7 and a groove in the frame. An eccentric pin g^8 , on the under side of the hub g^7 , enters the hole g^9 in the web g^2 of the double bolt. The movement of the lever g^5 to the right serves to withdraw the bolts g , g' from the seats in the end of the barrel which they normally engage, as shown in Fig. 3, and permits the gun to be broken.

An L-shaped plunger h , shown in Figs. 4, 5, 6, 7, 9 and 14, is supported for vertical movement in the side of the frame and is seated upon a spring h' , having its horizontal arm h^2 extended forward through a slot in the face of the frame. When the locking lever g^5 is swung to the right and the locking bolts are withdrawn, the stop or plunger h is raised by the spring h' so that its upper end stands in the path of the web g^2 of the locking bolts, thereby holding the bolts back so that the gun can be closed, and in the last of the closing movement of the gun the rear end of the barrel, below the chamber, at the left hand side, strikes the projecting horizontal arm h^2 of the stop and pulls the stop down against the pres-

sure of the spring, thereby withdrawing the upper end of the stop from the path of the web of the double locking bolt and permitting the bolt to snap forward to engage and lock the barrel in firing position.

The operation of the various parts of the gun has been described and no further explanation of the operation of the gun will be required. It will be understood that various changes in details of construction and arrangement can be made without departing from the spirit of the invention, which is not limited to the particular construction shown and described herein, except as pointed out in the claims.

I claim as my invention:

1. In a firearm, the combination of a frame having at its forward end a cylindrical bearing surface and having side flanges with a rearwardly facing bearing surface formed about the same center as the forwardly bearing surface, and a barrel provided with a seat to conform to the forwardly facing bearing surface and a curved shoulder conforming to and coöperating with the curved bearing surface of the corresponding side flange of the frame.

2. In a firearm, the combination of a frame having at its forward end a cylindrical bearing surface and having side flanges with rear ends curved about the same center as the forward end of the frame, and a barrel provided with a seat conforming to the forward bearing of the frame and having forwardly facing shoulders conforming to and coöperating with the curved rearwardly bearing surface of the side flanges.

3. In a firearm, the combination of a frame having a cylindrical forwardly facing bearing surface and having side flanges with rearwardly facing bearing surfaces curved about the same center as the forwardly bearing surface, a barrel adapted to be received between the flanges of the frame and having forwardly facing shoulders to coöperate with the bearing surfaces of the side flanges, and a fore-end detachably secured to the barrel and having a bearing seat for the barrel conforming to the forward bearing surface of the frame.

4. In a firearm, the combination of a frame and a barrel having coöperating open bearing surfaces curved about the same center, whereby the barrel is mounted hingedly and detachably on the frame, the barrel having a downwardly extending rib within the frame, the rib and the frame having coöperating shoulders independent of the hinge mounting to prevent the lifting of the barrel at the forward end of the frame.

5. In a firearm, the combination of a barrel having a depending shouldered lug, a fore-end, a spring-pressed plunger carried by the fore-end to engage the lug of the bar-

rel, and a cam lever pivoted on the fore-end and co-operating with the plunger to disengage the same from the lug.

6. In a firearm, the combination of a frame having a forwardly facing open bearing surface and a rearwardly facing open bearing surface, both bearing surfaces being curved about the same center, a barrel having open bearing surfaces conforming to the bearing surfaces of the frame and interengaging devices carried by the frame and the barrel to prevent the lifting of the barrel at the forward end of the frame when the gun is closed.

7. In a firearm, the combination of a frame having a forwardly facing open bearing surface and a rearwardly facing open bearing surface, both bearing surfaces being curved about the same center, a barrel having open bearing surfaces conforming to the bearing surfaces of the frame and cooperating shoulders arranged to interengage when the gun is closed and thereby prevent the lifting of the barrel at the forward end of the frame. 25

This specification signed this 26th day of Sept., A. D. 1919.

EDWARD E. REDFIELD.
